UNITED STATES PATENT OFFICE.

BRADFORD B. BABBITT, OF BROOKLYN, NEW YORK.

SELF-SOAPING DISH-MOP.

SPECIFICATION forming part of Letters Patent No. 743,132, dated November 3, 1903.

Application filed December 4, 1900. Serial No. 38,634. (No model.)

To all whom it may concern:

Be it known that I, BRADFORD B. BABBITT, of Brooklyn, in the county of Kings, State of New York, have invented a new and useful 5 Self-Soaping Dish-Mop, of which the following is a specification.

My invention relates to improvements in the construction of dish-mops so as to provide means whereby a supply of soap or other 10 ingredients may be stored and distributed in a thoroughly-dissolved state to the interior and exterior of the mass of material forming the mop proper and to assure a continual supply of soap to the mop while in the act of 15 washing dishes or other utensils.

In the accompanying drawings, forming part of this specification, Figure 1 is a perspective view of the mop complete with the reservoir or soap-receptacle attached, together with the handle. Fig. 2 is a sectional view of the same without the handle and more particularly shows the manner in which the mop material is bound around the mop-head, so as to form a space within the mop 25 material for the purpose to be hereinafter set forth.

Ordinary mop-yarn or mop material A is securely bound around a specially-constructed mop-head B, said mop-head being made of 30 wood in order to serve the purpose of this specification; but I wish it understood that I in no wise confine myself to wood alone in its construction, said mop-head B being of sufficient diameter to form a space C within the 35 mop material A, space C corresponding with the diameter of the mop-head B at its upper end and gradually diminishing and finally terminating at a point where a portion of the mop material A is bound together by stout 40 cord a, the point of binding being of a sufficient distance below the mop-head B to preserve a space C directly below the mop-head B. The mop-head B is provided with an opening or passage D, leading from the space 45 C to the interior of the cylinder E, the mop-head B forming a bottom to the cylinder E, to which it is firmly attached. Cylinder E is constructed of metal and is designed to contain soap or other compounds. Said cylinder 50 E is provided with a number of perforations f. The upper end of cylinder E is provided

with an ordinary thread turned upon itself in the ordinary screw form and in such a manner as to accept a corresponding thread which the handle G is provided with. The 55 handle G is by means of these corresponding threads attached or detached to the cylinder E at the will of the operator, and by thus removing the handle G cylinder E may be filled with soap or other compounds whenever necessary, and by the replacing of the handle cylinder E may thereby be closed.

Having described the construction of my invention, I will now describe the method by which the contents of the cylinder E is distributed after having been dissolved to the exterior and to the interior of the mop material while the mop is being used with water, as is intended. The soap or other compounds having first been placed within the cylinder 70 E, the handle G is securely screwed into place and the lower portion of the mop, or that portion comprising the mop material A a, is plunged into the water. Space C is filled with water immediately. The constant agitation of the mop in the act of washing the dish or other utensil designed to be cleaned is sufficient to drive the water in space C up through the opening D in the mop-head B into the cylinder E. A portion of the contents of cylinder E is thereby dissolved, and as it passes out of the perforations f the mop material is kept soapy and the water also all through the operation of washing dishes.

Having described the construction and the 85 manner of using my invention, what I claim is—

The combination of a head provided with a longitudinal passage, mop material bound to the outside of the head and leaving a space 90 within said material, and a cylindrical soap-receptacle having perforated sides attached to the mop-head, and communicating with the passage in the said head.

In testimony whereof I have signed my 95 name to this specification in the presence of two subscribing witnesses.

BRADFORD B. BABBITT.
